UNITED STATES PATENT OFFICE.

LUTHER F. COBB, OF PROVIDENCE, RHODE ISLAND.

TELEPHONE-BELL CUT-OUT.

SPECIFICATION forming part of Letters Patent No. 655,849, dated August 14, 1900.

Application filed January 6, 1900. Serial No. 637. (No model.)

To all whom, it may concern:

Be it known that I, LUTHER F. COBB, of Providence, in the county of Providence and State of Rhode Island, have invented certain 5 new and useful Improvements in Telephone-Bell Cut-Outs; and I do hereby declare that the following is a full, clear, and exact description thereof, reference being had to the accompanying drawings, and to the letters of 10 reference marked thereon, which form a part of this specification.

This invention relates to that class of electric cut-outs used in telephone systems where more than one bell is included in one circuit. 15 It is fully explained and illustrated in the specification and the accompanying drawings.

Figure 1 shows the instrument in elevation and a diagram of the operating-lines. Figs. 20 2, 3, and 4 represent the different positions of the indicating-plate in four instruments on the same wire or line. Fig. 5 shows a series of telephone-bell cut-outs connected in multiple.

25 The object of this invention is to avoid the necessity on circuits including more than one bell of ringing any of the bells except the one that is desired to communicate with.

The construction and operation are as follows:

30 A is a circular disk, made of some non-conducting material—such as hard rubber, for instance. This disk A is turned by clockwork (not shown) or may be operated by any motive power. This disk A is held from turning when not in use by means of a spring-catch B, which is arranged to drop into a notch a 35 in the edge of the disk when it comes under it. The catch B is made of soft iron or steel and is drawn up out of the notch a when it is desired to have the disk turn by means of an electric magnet C, which will attract the catch and raise it out of the notch when the magnet is energized by an electric current passing through its coils.

35 D D' are two metallic knobs or points fastened on the free ends of the metallic rods E E', respectively, and the rods are held at their outer ends in the posts F F', so that the 40 points will just clear the surface of the disk. A metallic plate G, of a segment shape and occupying about one-eighth of a circle, is made

fast on the face of the disk and is sufficiently raised above the surface of the disk to insure its contact with the balls D D' as the plate 55 passes under them.

Each bell on the circuit is provided with one of the instruments—that is, the electromagnet C, the spring-catch B, the two rods with points D D', and the disk with the plate G, only 60 that the plate G is placed differently on each of the four disks, as represented in Figs. 1, 2, 3, and 4, quartering to each other when the notch a is held by the catch B. The clock-work of each instrument is regulated to turn 65 each disk in the same space of time—say, for illustration, twenty-five seconds. In the first instrument the plate G is set on the right hand of the disk A, as in Fig. 1. The plate for the second bell is set on the lower quarter 70 of its disk, as in Fig. 2, the plate for the third bell is set on its disk on the left hand of the disk, as in Fig. 3, and the plate for the fourth bell is set on the upper quarter of its disk, as in Fig. 4. The two wires b and c, 75 which are usually connected with the bell, are connected in this case with the electromagnet C at L and M, and when the push-button J is pressed the current will pass through the electromagnet-wires and cause the magnet to 80 attract and raise all the catches D of the four instruments and allow each disk to be turned by its own clockwork at the same moment, and if the sender of the signal wants to call 85 up the first bell on the circuit five seconds are allowed for the plate on the first disk to come under the points D and D'. Then by again pressing the button the current will pass down through the wire and points around to the bell at N and ring it; but if it is the second bell that is to be called up ten seconds are 90 allowed the plate on the second bell-disk to come under the points D D', when by pressing the button the current will pass through them and ring the second bell, and in like manner a wait of fifteen seconds would make 95 a connection with the third bell, and twenty seconds would make a connection to ring the fourth bell. The spaces of time are only used for illustration, as they may be much shorter, 100 and the number of bells on the circuit may be more or less, the only change that would have to be made would be in the number of plates used and in dividing the face of the

disk into regular spaces, according to the number of plates and bells.

5 In Fig. 5 is shown a series of telephone-bell cut-outs connected in multiple and in which the operation is substantially the same as with a single cut-out. These cut-outs may be arranged any suitable distance apart upon the telephone-line and are connected substantially as shown.

10 Having thus described my improvements, I claim as my invention and desire to secure by Letters Patent:

1. A revoluble non-conducting disk A provided with a metallic segment upon its side, 15 the two stationary rods provided with points upon their ends, and which have their upper ends to extend inwardly past the outer edge of the disk so as to come in contact with the segment, a catch for engaging with a notch 20 in the edge of the disk, and an electromagnet for operating the catch, combined with the push-button, the wires b, c, connected therewith, wires extending from the electromagnet and connecting with the wires b, c, the wire 25 b being connected to one of the rods, an alarm-bell connected to the wire c, and a wire

extending from the alarm-bell to the other stationary rod; the parts being combined and arranged to operate, substantially as shown.

2. In a cut-out for telephone-bells, two or 30 more revoluble disks having plates of metal attached to their faces, the shunt-circuit, points connected to the shunt-circuit and held so as to make contact with the plates, thereby closing said circuit, and catches to hold said 35 disks from turning, combined with electromagnets, of high resistance connected in multiple, which allows them to be energized by either a continuous or an alternating current to release said catches from the disk, a bell 40 for each disk connected with its contact-points so as to ring the bell when said disk closes the circuit by coming in contact with said points, substantially as described.

In testimony whereof I have hereunto set 45 my hand this 27th day of December, A. D. 1899.

LUTHER F. COBB.

In presence of—
BENJ. ARNOLD,
M. E. CLEVELAND.
